PAINT BRUSH
George H. Stormyr, P.O. Box 275, Silverton, Oreg.
Filed Jan. 10, 1964, Ser. No. 336,913
2 Claims. (Cl. 15—201)

This invention relates to paint brushes, and more particularly to a paint brush construction which affords thorough cleaning of the bristles.

It is generally recognized in the art that the useful life of a paint brush is limited primarily by the accumulation of dried paint within the bristles, resulting from the inability to thoroughly clean the bristles after each use. In attempting to solve this problem, and hence to obtain longer service life, paint brush constructions have been provided heretofore in the form of multi-section bristle components adapted to be separated to facilitate more thorough cleaning. However, these proposed structures are characterized by being rather complex and therefore too costly for general use. Further, they are cumbersome and difficult to assemble and disassemble, they are subject to improper assembly due to the accumulation of paint in the interfitting parts, and they are not leak proof.

Accordingly, it is the principal object of the present invention to provide a paint brush of the multi-section type which can readily be opened for inspection or cleaning simply by retracting or removing a ferrule securing the sections in the closed position and as readily closed with precision and speed ready for use.

Another important object of this invention is the provision of a paint brush of the multi-section type which is characterized by being leak proof when assembled.

A further important object of this invention is the provision of a paint brush of the multi-section type which is characterized when assembled by having a substantially continuous and uninterrupted working surface of bristles.

A still further important object of this invention is the provision of a paint brush of the multi-section type which is of simplified construction for economical manufacture.

The foregoing and other objects and advantages of this invention will appear from the following detailed description, taken in connection with the accompanying drawing in which:

FIG. 1 is a view in side elevation of a paint brush embodying the features of the present invention, the several sections thereof being shown by dash lines as separated from each other.

FIG. 2 is an end elevation of the paint brush shown in FIG. 1;

FIG. 3 is a fragmentary sectional view taken along the line 3—3 in FIG. 1 and showing details of assembly of the bristle and handle components of each section of the paint brush;

FIG. 4 is a sectional view taken along the line 4—4 in FIG. 1 and showing the manner in which the paint brush sections are secured together;

FIG. 5 is a sectional view taken along the line 5—5 in FIG. 1 and showing the manner in which the paint brush sections are retained in assembled condition;

FIG. 6 is a view in side elevation of a modified form of multi-section paint brush embodying the features of the present invention;

FIG. 7 is an end elevation of the paint brush shown in FIG. 6;

FIG. 8 is a fragmentary sectional view taken along the line 8—8 in FIG. 6; and

FIG. 9 is a sectional view taken along the line 9—9 in FIG. 6.

In its general concept, the paint brush of the present invention comprises a plurality of sections each constitut-

2

ing an integrated assembly of a handle component and a bristle component, the plurality of sections being connected together pivotally adjacent the outer ends of the handle components and supported releasably in assembled condition by means of a removable encircling ferrule.

Referring first to the embodiment illustrated in FIGS. 1—5 of the drawing, the paint brush includes a plurality of sections each including a thin, flat handle component 10 terminating at one end in a widened head 12 to which is secured the thin, flat bristle component 14. Although four such sections are illustrated in the drawing, it will be understood that the number of sections may be varied as desired.

15 The bristle component may be attached to the handle head by any conventional procedure, although the arrangement best illustrated in FIG. 3 is preferred. Thus, the flat, thin mass of bristles are bonded together at their butt ends in a base 16 of rubber or other suitable bonding material including the many varieties of cements, adhesives and thermo-setting and thermo-plastic resins.

20 The bonded base end of the bristle component then is placed in abutment with the face end of the handle head, preferably with a layer of adhesive interposed therebetween, and the joint then is overlapped with an encircling band 18. In the preferred embodiment illustrated this band is formed by first coating the joint with a layer of synthetic polyester resin (incorporating the usual accelerator catalyst), then wrapping about the coated joint 25 a layer of glass fiber cloth, and finally coating the cloth with a second layer of polyester resin. This band is quite thin and yet is extremely strong and rigid. Moreover, the external surface of this band is sufficiently smooth to provide a liquid tight seal between adjacent bands 30 when the brush sections are assembled together, as explained more fully hereinafter.

35 Having thus formed the plurality of sections of the paint brush, they are assembled together as a stack (FIG. 2). Aligned transverse openings 20 adjacent the outer 40 ends of the handle sections freely receive therethrough a headed pivot pin by which the brush sections are secured together for relative pivotal movement. Although the pivot pin may be a rivet or other device which forms a permanent attachment, a detachable pivot connection is 45 preferred to enable disassembly of the brush sections. Accordingly, the pivot pin best shown in FIG. 4 is in the form of an elongated stem 22 provided at one end with an enlarged head 24 and having at its opposite end an internally threaded bore adapted to receive the threaded screw shank 26 projecting from the enlarged screw head 28.

50 The pivotally connected sections are secured releasably in assembled, overlapping condition by means of an encircling ferrule 30. This ferrule may be made of metal or other suitable material. In the embodiment illustrated it is made as a band of glass fiber cloth or mat reinforced by polyester resin. The ferrule is proportioned to slip freely over the assembly of handle components and to encircle the assembled heads, being retained thereon by 55 frictional contact. For this purpose it is preferred that the heads be tapered outwardly toward the bristle components and the ferrule be tapered correspondingly, to provide a wedge connection therebetween.

60 With the brush sections secured together in overlapping relation by the ferrule, the interfacial contact between the adjacent bands 18 and ferrule provide a liquid tight seal which prevents paint from running from the bristles through the handle sections.

65 When it is desired to clean the brush, the encircling ferrule is slipped off of the assembled handles and the sections are pivoted relative to each other about the pivot

pin 22, in fan-like manner, to separate the plurality of bristle components, as illustrated in dash lines in FIG. 1. The plurality of thin bristle components then may be washed thoroughly in solvent to effect maximum cleaning and insure complete removal of paint. Thereafter, the brush sections are pivoted to the mutually overlapping position and the ferrule reinstated.

If desired, the brush sections may be separated from each other, by disconnection of the pivot pin 22, and each individual brush section may be utilized as a separate paint brush. Alternatively, the sections may be assembled together in any desired numbers, it being required only that ferrules 30 of appropriate sizes be provided for the various assemblies.

Referring now to the embodiment illustrated in FIGS. 6-9 of the drawing, the outermost handle components 32 and 34 are provided with handle heads 36 and 38, respectively, which are substantially L-shaped in cross section (FIG. 9). These heads support correspondingly L-shaped bristle components 40 and 42, respectively, and are arranged relative to each other to define the outer periphery of the brush. Thus, one outer bristle component defines one face and one side of the brush and the other bristle component defines the other face and other side of the brush. This provides a composite brush in which the mass of bristles has a substantially continuous and uninterrupted peripheral surface, as distinguished from the interrupted sides of the bristle assembly shown in FIG. 2.

The next inner handle components 44 and 46 also are provided with L-shaped handle heads 48 and 50, respectively, supporting L-shaped bristle components 52 and 54, respectively, arranged to conform to the shape of the outer components. The central space between these inner brush sections is filled with a central handle component 56 having a flat, thin handle head 58 which preferably does not support a bristle component. The central head thus forms a plug, and the space 60 outwardly of it and surrounded by the inner bristle components forms a paint reservoir, as is well known.

The brush sections are secured together pivotally adjacent the outer ends of the handle components, as is the first embodiment described, and are secured releasably in assembled condition by the removal ferrule 30, also as previously described. Thus, the manner of assembly and disassembly is substantially the same for both embodiments.

From the foregoing, it will be appreciated that the present invention provides a paint brush of considerable versatility, which is capable of being thoroughly cleaned with speed and facility, which may be disassembled into a plurality of individual paint brushes for separate use, and which is of simplified construction.

It will be apparent to those skilled in the art that various changes may be made in the structural details described hereinbefore without departing from the spirit of this invention and the scope of the appended claims.

Having now described my invention and the manner in which it may be used, what I claim as new and desire to secure by Letters Patent is:

1. A paint brush comprising

(a) a plurality of brush sections arranged in a stack and each including a bristle component and a handle component having a bristle mounting head,

(b) pivot means securing the handle components together adjacent the ends opposite the heads, and

(c) ferrule means comprising a band releasably encircling and frictionally engaging the mounting heads for releasably securing the stack of brush sections together,

(d) the mounting heads and band being tapered outwardly in the direction of the bristle components.

2. The paint brush of claim 1 wherein there are at least three brush sections and the outer mounting heads and bristle components are L-shaped in cross section and arranged when the sections are in assembled condition to form a substantially continuous peripheral surface of bristles about the bristles of the inner brush sections.
